(57) **CLAIM**

The ornamental design for a drip clip, as shown and described.

DESCRIPTION

FIG. 1 is a perspective view showing our new drip clip;

FIG. 2 is a right side view thereof;

FIG. 3 is a left side view thereof;

FIG. 4 is a top view thereof;

FIG. 5 is a bottom view thereof;

FIG. 6 is a front view thereof, and,

FIG. 7 is a back view thereof.

The broken lines shown in the figure represent a portion of the drip clip and form no part of the claimed design.
